UNITED STATES PATENT OFFICE.

WILLIAM LEE HANLEY, JR., OF BRADFORD, PENNSYLVANIA.

DRY-PAN GRINDING APPARATUS.

Application filed October 14, 1924. Serial No. 743,538.

My invention consists in the novel features hereinafter described, reference being had to the accompanying drawings, which show one embodiment of the same, selected by me for 5 purposes of illustration, and the said invention is fully disclosed in the following description and claims.

In the construction of dry pan grinding apparatus, which comprises as essential elements, a horizontally disposed rotary disc or pan upon which are supported heavy, freely revoluble mullers supported between vertically movable pivot arms, it has been proposed to provide a vertically disposed annular rim supported stationarily, slightly above the outer marginal portions of the disc or pan and adjustable vertically with respect thereto, to form an annular delivery slit or outlet, through which the ground product may be discharged when it has been reduced to particles of sufficiently small size as to pass between the lower edge of the rim and the upper face of the disc or pan, thus dispensing with the use of screens in 15 the disc or pan which were formerly employed. As the disc or pan is rotated, the clay or other material to be ground is carried under the freely revoluble mullers, which in the larger sizes of the machines 20 may weigh several tons each, for the purpose of breaking up the material to be ground into fine particles, and the mullers are therefore obliged to rise and fall in passing over the lumps of the material acted upon and 25 the retaining arms for the mullers are necessarily subjected to severe torsional strains in maintaining the mullers at all times in vertical position. As a consequence, these arms frequently break and usually at or near their 30 points of pivoting. It has also been found to be a very difficult matter to secure the proper adjustment between the lower edge of the annular rim and the upper face of the disc at all points around the disc and even 35 when this adjustment has been obtained in a manner at least satisfactory for commercial purposes, it is difficult to positively hold the rim in its adjusted position at all 40 points around the same. It is customary 45 to provide the stationary rim usually at two or more points with inwardly extending 50 scraper plates or deflector plates for the purpose of deflecting the material on the disc or pan, which has a tendency to work 55 toward the periphery by centrifugal force, back toward the center of the disc or pan

in order to have it pass under the mullers over and over again until reduced to the proper degree of fineness. The positions of these scrapers vertically with respect to the 60 pan is also regulated by the same adjusting devices which support the rim in its adjusted position, and the jarring contact of the material on the pan against these scrapers is imparted to the rim and has a 65 tendency to disturb the adjusting devices therefor. If the rim is adjusted too high the material will escape from the apparatus in a more coarse condition than is desired, and if the rim approaches the pan too closely the 70 discharge of the finely ground material is prevented or retarded or the material is ground more finely than is desired or necessary.

One of the objects of my present invention 75 is to provide supporting means for the mullers, which will strengthen the supporting members and enable them to resist the torsional strains to which they are necessarily subjected, while at the same time permitting 80 the vertical movement of the mullers in passing over the material to be ground. I accomplish this result by providing a horizontally disposed supporting frame for each muller comprising arms located on opposite 85 faces of the muller and connected with the muller by means permitting the rotation of the latter, the said frame being pivotally supported at one end upon a stationarily supported pivotal connection, and the said 90 arms adjacent to the other end of the frame being rigidly connected together and capable of vertical movement. In practice I prefer to employ a spring or other yielding support for the non-pivoted end of the muller frame. 95 I also prefer to form the annular rim of a plurality of sections, either two sections or more, having overlapping end portions to prevent the material from escaping except through the delivery slit formed between the 100 lower edges of said sections, and the upper surface of the disc. Each rim section is rigidly supported at a plurality of points by independently adjustable means which 105 will not be affected by any jarring to which the rim sections may be subjected and certain of said rim sections or each of them is or are provided at one end with a portion extending inwardly toward the axis of the pan and forming a scraper or deflector. 110 This construction permits of a ready adjustment of the entire rim with respect to the

upper surface of the pan, as each section is susceptible to independent adjustment at various portions thereof, without affecting the adjustment of the other sections, and as the adjusting means and the supporting means of both are incapable of being affected accidentally by any jarring to which the machine is subjected, the said sections will be retained at all times in the positions to which they are adjusted. On account of the great weight of the mullers and the severe attrition to which the upper surface of the pan is subjected, I prefer to provide the pan with a renewable grinding surface, which consists of an annular ring formed in sections, for instance in four quadrantal sections, and having beveled portions at their outer and inner edges, the outer beveled portions interlocking with undercut portions formed directly on the pan adjacent to the peripheral edge thereof, and the inner beveled portions being engaged by blocks or wedges bolted or otherwise secured to the pan, thus holding the quadrantal segments in position, but permitting them to be renewed without renewing the entire disc or pan. These quadrantal segments are preferably made of extremely hard material to withstand the wear to which they are subjected.

In the accompanying drawings I have shown so much of a dry pan grinding apparatus as is necessary for a clear understanding of my present invention. In these drawings,

Fig. 1 represents a plan view of the apparatus, partly in section.

Fig. 2 represents a partial vertical section of the apparatus on the line 2—2 of Fig. 1.

Fig. 3 is an enlarged detail view illustrating one of the supports for the adjacent overlapping ends of two of the rim sections.

Fig. 4 is a detail sectional view on line 4—4 of Fig. 3.

Fig. 5 is a detail section on line 5—5 of Fig. 3.

Fig. 6 is a sectional view of one of the intermediate supports for a rim section.

Fig. 7 is a plan view of the disc or pan showing the segmental wearing plates.

Fig. 8 is a detail of a modified form of adjusting means for the rim sections.

Referring to the drawings, 1, represents the horizontally disposed pan or disc mounted upon the vertical shaft, 2, supported at its lower end in a heavy step bearing, 3, which is mounted on a suitable foundation. In this instance I have shown foundation walls, 4—4, or abutment of concrete connected by transverse girders, 5, upon which the step bearing, 3, rests, the foundation being trussed and strengthened in any usual or desired manner. In this instance I have shown two mullers, indicated at 6—6, each of which is provided with shaft portions or trunnions, indicated at 7, which may be provided in any desired manner, said shaft portions projecting laterally from the opposite faces of the muller. Each muller is provided with a supporting frame for maintaining it in vertical position and holding it in proper position with respect to the pan, 1. In this instance each of said frames comprises a pair of substantially parallel arms, 8, having portions extending on opposite faces of the muller and provided with bearings, indicated at 9, to engage the shaft portions, 7, of the muller so as to permit the free rotation of the muller with respect to the frame. The arms, 8—8, are connected at one end and pivotally supported in a substantially horizontal position adjacent to the shafts of the mullers. They are shown as connected to a sleeve, indicated at 10, to which they are rigidly secured and they may be formed integrally with the sleeve, if preferred. Each of the sleeves, 10, is pivotally mounted on a shaft, 11, which is stationarily supported in this instance being held in clamps, 12, three of which are shown, secured to angle plates, 13, having vertical flanges embedded in one of the concrete foundations or abutments, 4. The opposite end portions of the arms, 8, which extend past the bearings, 9, and are vertically movable, and rigidly united together. This may be accomplished in many ways. In the present instance I have shown the vertically movable ends of the arms, 8, provided with converging portions, indicated at 8^a, rigidly secured to a connecting bracket, 8^b, riveted, bolted, or otherwise secured thereto, but obviously the supporting frame for the muller may be cast integrally, with the sleeve arms and connecting bracket portions in one piece, if desired, or they may be formed of separate pieces of either cast or wrought metal, and suitably united as preferred. It will be seen that by extending the arms, 8, on the opposite side of the muller shaft from the point of pivoting of the frame, and uniting said arms rigidly, a very rigid supporting frame is provided which will enable said frame to more readily resist the torsional strains to which it is subjected and prevent the breaking of the arms adjacent to their points of pivoting. I prefer to construct these frames of wrought metal, wrought iron or steel, to further insure against the breaking of the arms, 8, adjacent to their points of pivoting which is more likely to occur where cast iron or cast steel is employed. They may, however, be formed of cast iron or cast steel, if desired, and in either separated pieces bolted together or as a unitary one piece structure, as preferred. I also prefer to provide a yielding support for the vertically movable end of each of said muller supporting frames, and in this instance I have shown each of said frames provided with a spiral spring, indicated at 14. As

best illustrated in Fig. 2, I prefer to provide the connecting bracket, 8^b, on its lower face with a cylindrical socket, indicated at 8^c, and to provide a similar socket, 8^d, supported on a bed plate, 15, secured to angle plates, 16, having flanges embedded in the concrete foundations of the abutment, 4, opposite that which supports the pivoted end of the frame, and to use a vertically disposed spiral spring, 14, the ends of which are engaged by sockets, 8^e and 8^d. A very heavy spring is employed and assists in cushioning and steadyng the outer or vertically movable end of the muller frame and relieves the entire apparatus to a certain extent from objectionable jarring when the machine is in operation.

The upper face of the pan or disc, 1, is provided with an annular rib, indicated at 17, the inner face, 18, of which is undercut. The upper face of the disc or pan is also provided with a renewable wearing surface consisting of a plurality of segmental plates, 19, four quadrantal plates being shown. Each of these plates, 19, is provided with a recess, 19^a, around its peripheral edge fitting the annular retaining rim, 17, of the pan, 1, the outer edges, 19^b, of the segments, 19, however, extending over the retaining rim so as to provide the disc with a perfectly smooth horizontal wearing surface to the extreme edge of the same. The inner edges of the segments, 19, are also beveled as indicated at 20, and are held in place by segmental wedges, 21, surrounding the hub, 1^a, of the disc and held in place by suitable bolts, 22. The upper end of the shaft 2, is supported in any desired manner, in this instance by a bearing, 23, supported between girders, 24, secured to masonry or other supports, indicated at 25. It will be understood that the shaft, 2, will be driven in any suitable manner, and by any suitable source of power, thereby rotating the horizontal pan or disc, 1, and effecting the rotation of the freely revolving mullers, 6, as usual in dry pan grinding apparatus. In the present instance I have shown the shaft, 2, provided with a driving gear, 26, meshing with a driving pinion, 27, on a shaft, 28, which in this instance is shown connected to the armature shaft of an electric motor, 29. The shaft, 2, however, may be driven in any usual or preferred manner.

Surrounding the material on the dry pan or disc, 1, adjacent to the peripheral portions thereof, is a vertically disposed retaining rim, preferably formed of sections, each of which sections overlaps portions of another section, so as to prevent the accidental escape of material. Each of these rim sections is supported at a plurality of points, and has an end portion, extending inwardly toward the center of the pan, to serve as a scraper or deflector. In the present instance

I have shown this rim composed of two sections, but it will be obvious that three, four or more sections may be employed, if found advantageous. In the present instance, each of these rim sections, consists of a curved, vertically disposed metal bar, indicated at 30, formed by bending a flat bar of metal into the proper form, each section being preferably provided at one end with adjustable supporting means, which is located above and closely adjacent to the periphery of the pan or disc, 1, said rim section following closely the curvature of the periphery of the rim for a considerable distance, and then curving inwardly, as indicated at 31, toward the center of the disc or pan, to form a scraper section, the scraper section of each rim section extending past the opposite end of the adjacent section so as to make the rim sections overlap for a considerable distance. In order to support the rim sections and provide for their vertical adjustment with respect to the pan or disc, I prefer to provide adjustable supporting means engaging each section at three or more points, as herein shown, three points being my preferred construction. In this instance each rim section, 30, has at one end a supporting hanger, 32, shown enlarged in Figs. 3 and 5, having bifurcated portions, 33, fitting the rim section, 30, and secured thereto by rivets or bolts, 34, the said hanger being provided with a vertical aperture, indicated at 35, through which a vertically disposed adjusting screw passes for securing the vertical adjustment of the rim section at that point. In Figs. 3 and 5, the aperture, 35, is shown as a threaded aperture and engages a vertically disposed adjusting screw, 36, provided at its lower end with a reduced bearing portion, 37, engaging a bearing aperture in a supporting bracket, 38, the upper end of the screw being provided with a bearing portion, 39, passing through a bearing aperture in the bracket, 38, the bearing portion, 39, being of larger diameter than the screw itself. The screw, 35, is also provided with a shank portion, 40, of smaller diameter than the bearing portion, 39, terminating at its upper end in a polygonal portion, 41, the screw being held in the bracket by a cap plate, 42, fitting the shank portion, 40, and secured to the bracket by screws or bolts, 43, as clearly shown in Fig. 5. It will be seen that by placing a wrench or key over the polygonal head of the screw, 35, and rotating the screw, the hanger, 32, and the adjacent end of the rim section to which it is connected will be adjusted vertically and with the utmost nicety and that the rim section will be held in any position to which it may be adjusted against accidental displacement. The bolts, 34, connecting the hanger, 32, with the rim section are horizontal so that they are not

affected by jarring, and there can be no change in the position of the rim section except by manipulation of the adjusting screw, 36.

5 In Fig. 8 I have shown a slightly different form of adjusting means, which comprises in this instance a vertically threaded bolt, 35^a, extending through the bracket, 38^a, and held in place by a nut at its lower end, the 10 said bolt passing through an unthreaded aperture, indicated at 32^b, in the clip or hanger, 32^a, which is secured to the adjacent end of the rim section by the horizontal bolts or rivets, 34^a. The bolt, 35^a, is provided with 15 adjusting nuts, 35^b, above and below the hanger, 32^a, and by adjusting these nuts, the vertical adjustment of the adjacent end of the rim can be secured and the parts will be held in adjusted position by setting up 20 the nuts, 35^b in opposite directions so as to lock each other. I do not limit myself to either of the specific adjusting means shown, as variations may be made therein within 25 the spirit of my invention.

25 The bracket, 38, illustrated in Figs. 3 and 5, is conveniently formed as a part of or attached to the central bearing, 12, for the pivot shaft, 11, upon which the muller supporting frames are pivoted, and I prefer to 30 so construct this bracket, 38, that it will support the adjusting means for the overlapping portions of two adjacent sections. This is illustrated in plan in Fig. 3 and in Fig. 35 4—4 of Fig. 3, which illustrates the manner in which the bracket, 38, is conveniently formed as a part of the bearing, 12, although obviously it may be supported in other ways. In Fig. 4, 31 represents the 40 overlapping portion of the adjacent rim section, which is provided with a hanger, 44, rigidly secured thereto by means of horizontal rivets or bolts, 45, and provided with a boss, 46, having a vertical opening therein 45 to cooperate with the adjusting means. As shown in Fig. 4, the aperture in the boss, 46, is threaded and engages a screw, 136, constructed exactly in accordance with the 50 similar screw illustrated in Fig. 5, and previously described, the various parts being given the same reference numbers with 100 added.

55 I also prefer to provide each rim section with one or more intermediate brackets and adjusting devices so that each rim section will be supported and will be adjustable at three points. In the present instance I have shown each rim section provided with an intermediate hanger, 50, illustrated in detail 60 in Fig. 6, and adjacent thereto I provide a supporting bracket, indicated at 51, suitably mounted on the frame or foundation of the apparatus, and provided with a vertically disposed adjusting screw for the hanger, 50.

65 The hangers, 50, are each secured to the

adjacent rim section, 30, by horizontally disposed rivets or bolts, 52, and the bracket therefor is provided with a vertical opening threaded internally to engage the adjusting screw, 236, having bearing portions, 237—79 75 239, adjacent to its ends engaging bearings in the brackets, 51, and provided at its upper end with a polygonal portion, 241, to receive a wrench or key for turning the screw. As illustrated in Fig. 6, I may provide the screw with means for locking it positively against rotation, consisting in this instance of a locking plate, 242, having a polygonal aperture therein, to fit the polygonal portion, 241, of the screw, said plate 80 being held in place on the bracket by an attaching screw, 243. With this construction it is necessary to detach the plate, 242, before attempting to adjust the screw, 236, and this plate will hold the screw positively 85 against the possibility of accidental displacement. It will be understood that I may provide all of the adjusting screws, 36, 136 and 236, with this locking device or keeper, illustrated in Fig. 6, if found necessary or desirable. 90

It will also be understood that in connection with each of the hangers, 32, 44, and 50, secured to the rim sections at different points I may employ the adjusting device illustrated 95 in Fig. 8 instead of the screws, 36, 136 and 236, if desired.

It will be seen that the rim sections, 30, are each capable of very ready adjustment, 100 as each section is provided with a screw threaded adjusting means adjacent to each end and at one or more points between, and that each section is adjusted so that its lower edge is at a uniform distance from the upper face of the pan or disc, 19. It will be seen 105 that the adjustment of one of the rim sections does not affect the other, and the difficulty of securing the desired adjustment of the rim to provide a uniform horizontal slit between its lower edge and the upper face 110 of the disc is greatly diminished. Where the rim is made in one piece it cannot be adjusted at any one point without loosening the adjusting devices at other points, and the adjustment of the integral rim at one 115 point will affect the adjustment of almost the entire rim so that it is a very difficult matter to accurately adjust the rim when made in a unitary structure. It will also be seen that by providing each of the rim sections with the overlapping portions extending beyond the end of the adjacent section, no material can escape between sections, and moreover the scraper portions, 31, 120 can be very conveniently formed integrally with the rim sections, and this enables them to be adjusted therewith, and also prevents the possibility of the scrapers, 31, becoming 125 at any time detached from the rim section. The specific construction of the screw 129

threaded adjusting devices illustrated in Figs. 3, 4, 5 and 6, is not herein claimed, as the same forms no part of my present invention, and other forms of adjusting devices, 5 such as that illustrated in Fig. 8, for example, may be employed in place of the particular parts illustrated in said figures.

What I claim and desire to secure by Letters Patent is:—

- 10 1. In a dry pan grinding machine, the combination with a horizontal rotatable pan and mullers, of a stationary rim located slightly above said pan and providing a discharge aperture between its lower edge and said pan, said rim being formed of separate sections, having overlapping portions, each of said rim sections being provided with a portion between its ends, curved substantially concentrically with the axis of the pan and having an integral end portion bent inwardly from said central portion and lying within the concentric portion of another section, and serving as a scraper to deflect the material on the pan away from the periphery thereof, each of said rim sections being 15 provided with outwardly extending brackets rigidly secured to said substantially concentric portions at intervals, stationary supporting means for each of said brackets provided with vertically adjusting means, for 20 securing the vertical adjustment of said substantially concentric portions of the rim sections, and said scraper portions thereof. 40
- 15 2. In a dry pan grinding machine, the 45
- 20
- 25

combination with a horizontal rotatable pan and mullers, of a stationary rim located slightly above said pan and providing a discharge aperture between its lower edge and said pan, said rim being formed of separate sections, having overlapping portions, each of said rim sections being provided with a portion between its ends, curved substantially concentrically with the axis of the pan and having an integral end portion bent inwardly from said central portion and lying within the concentric portion of another section, and serving as a scraper to deflect the material on the pan away from the periphery thereof, each of said rim sections being provided with outwardly extending brackets rigidly secured to said substantially concentric portions at intervals, stationary supporting means for each of said brackets provided with vertically adjusting means, for securing the vertical adjustment of said substantially concentric portions of the rim sections, and said scraper portions thereof.

In testimony whereof I affix my signature.

WILLIAM LEE HANLEY, JR.
